T. F. WAGONER.

Hulling Machine.

No. 24,595.

Patented June 28, 1859.

UNITED STATES PATENT OFFICE.

THOMAS F. WAGANER, OF TRENTON, NEW JERSEY.

MACHINE FOR HULLING AND SCOURING GRAIN.

Specification of Letters Patent No. 24,595, dated June 28, 1859.

To all whom it may concern:

Be it known that I, THOMAS F. WAGANER, of the city of Trenton, in the county of Mercer and State of New Jersey, have invented 5 a new and useful Improvement in the Rubbers of Machines for Hulling and Scouring Grain, Seed, &c.; and I do hereby declare that the following is a full, clear, and exact 10 description of the construction and operation of the same, reference being had to the annexed drawings, making part of this specification, in which—

Figure 1 represents a perspective view of the ordinary mill to which my improvement 15 may be applied. Fig. 2 is a transverse section of the same, together with a section of the runner or upper rubber.

The same letters of reference marked thereon indicate similar parts.

20 Thus A, B, are the posts, or uprights of the husk.

C, D represents the top covering or husk floor.

E, F is the bed stone or lower rubber.

25 G, H, I, J in Fig. 2, represents a section of the runner or upper rubber.

M, N, O indicates the hoop, or outer casting, usually placed over both the rubbers when the machine is in operation.

30 P, Q, R represents the spindle upon which the runner, or upper rubber, hangs; and by which it is carried around, over the bed stone or lower rubber.

S, T is the driving pulley, or gear wheel.

35 R represents the step in which the lower end of the spindle turns.

U, V, W is the eye of the runner or upper rubber, through which the grain passes from the hopper, down between the rubbers.

40 X, Y shows the spout through which the grain, or seed, is discharged from the rubbers, after it has been hulled or scoured.

The rubbers of machines in present use are either of stone or iron, or some other 45 hard unyielding substance, and therefore not adapted to the hulling, or scouring of grain or seed, without in a great degree breaking, grinding or otherwise injuring the grain in its passage between them during 50 the operation. To obviate this defect I pro-

pose to construct the rubbing surface of the rubber of india-rubber, gutta percha, or any other elastic substance at present known and suitable for this purpose. The india rubber and gutta percha may be combined together, 55 and manufactured and vulcanized as the same is sold in the market.

In Fig. 2, G, H, K, L represents a section of the lower portion of the runner, which I propose to make of the elastic substances 60 above mentioned. I do not wish to confine myself to the application of this elastic material to one rubber only, but in certain cases may prefer to have both the rubbers coated with this material. What I prefer 65 however for general use in the application of the elastic material to the upper runner or rubber, in connection with a bed stone for the lower rubber.

The operation of the machine being similar 70 to all other mills for hulling and scouring can be readily understood by those conversant with these subjects. The advantages of the rubber, as above described, over the ordinary hard surfaced rubbers, consists 75 in its elasticity; by which any kind of grain may be passed through, or under it, and hulled or scoured, without grinding the same, or in any way injuring the grain. In the hulling and scouring processes, the elasticity 80 of the rubber may be so regulated, to the various kinds of grain, or seed, to be operated upon, that should the grains be caught endwise between the rubbers in the operation, they would be enabled to turn 85 over, and pass through, without breaking the grain or materially injuring the same.

It will be understood that my improvement in the construction of rubbers consists 90 in using the surface of the elastic material directly in contact with the grain, or work to be performed, without being covered or coated with any hard unyielding material.

I am aware that india rubber has been 95 used in combination with a hard surface for the purpose of hulling grain, when the said rubber has been placed upon cylinders or in conical vessels. Hence I do not wish to lay a claim broadly to such a combination, nor do I wish to claim the combination of an 100

elastic surface with a hard surface, when the planes of said surfaces are placed out of a plane with the horizon, but

What I do claim is—

5. The combination of two surfaces, one of which is elastic and the other hard, when the planes of said surfaces are placed on a plane with the horizon, and one of them

having a circular motion for the purpose of hulling and scouring grain substantially as set forth.

THOMAS F. WAGANER.
